UNITED STATES PATENT OFFICE.

EDWARD B. WEBBER, OF COLLIERSVILLE, TENNESSEE.

CLOTHES-PIN.

SPECIFICATION forming part of Letters Patent No. 498,892, dated June 6, 1893.

Application filed September 24, 1892. Serial No. 446,812. (No model.)

To all whom it may concern:

Be it known that I, EDWARD B. WEBBER, a citizen of the United States, residing at Collierville, in the county of Shelby and State of

5 Tennessee, have invented a new and useful Clothes Pin or Holder, of which the following is a specification.

My invention relates to improvements in devices for securing clothes to lines during 10 the process of drying, the objects in view being to provide a simple, durable and easily operated device, which is permanently carried by the line and may be cheaply manufactured.

15 Further objects and advantages of my invention will appear in the following description, and the novel features thereof will be particularly pointed out in the appended claims.

Figure 1 is a perspective view showing my 20 improved clothes-pin or fastener in the operative position. Fig. 2 is a detail view of the fastener detached.

The clothes pin or fastener, which is shown at A, is provided with a body-portion, B, substantially rectangular in shape, at the ends of which are formed the depending fingers, C, C, in the form of loops, and at the center of which is a depending loop, D, provided at its lower end with a securing coil, E, which fits 25 upon the clothes line, shown at F. Between the depending fingers and the loop D are horizontal portions, which connect the fingers to the loop D, and convey the spring pressure of the latter to the former, whereby the lower 30 ends of the fingers are pressed firmly against the side of the line. The lower or closed ends of the looped fingers are curved or bent rearward or under the line, to conform to the surface of the latter, and provide more bearing 35 surface for the fingers.

The upper side or top of the rectangular body-portion of the fastener is formed by the

connected free ends of the wire composing the same, my improved pin being formed of a single piece of wire, as clearly shown in the 45 drawings.

In operation, the pins being permanently secured to the line are always in position to be used, and to engage an article of clothing therewith it is simply necessary to withdraw 50 the free end of one of the fingers from the line by a pressure thereupon, and slide the pin to a position in which said finger will engage the edge of the garment.

It will be noted that the pin is simple in 55 construction and may be readily operated.

Having thus described my invention, what I claim, and desire to secure by Letters Patent of the United States, is—

1. A clothes pin or fastener having a rectangular body-portion provided with terminal loops having rearwardly bent points and an intermediate loop terminating in a coil which receives the line, substantially as specified. 60

2. A clothes pin or fastener, formed from a single piece of wire, and having a rectangular body-portion, a central depending loop 65 terminating in a coil to receive the clothes line, and terminal depending loops, arranged upon opposite sides of the central loop and provided with bent lower ends or points, the contiguous sides of adjacent loops being connected by integral horizontally extending portions, and the terminals of the wire being connected at the upper side of the body-portion, 70 substantially as specified. 75

In testimony that I claim the foregoing as my own I have hereto affixed my signature in the presence of two witnesses.

EDWARD B. WEBBER.
